UNITED STATES PATENT OFFICE.

JOHN DOUGLAS, OF NEWARK, NEW JERSEY, ASSIGNOR TO THE SINGER
MANUFACTURING COMPANY, A CORPORATION OF NEW JERSEY.

THROAT-PLATE FOR SEWING-MACHINES.

SPECIFICATION forming part of Letters Patent No. 735,477, dated August 4, 1903.

Application filed January 6, 1903. Serial No. 138,034. (No model.)

To all whom it may concern:

Be it known that I, JOHN DOUGLAS, a citizen of the United States, residing at Newark, in the county of Essex and State of New Jersey, have invented certain new and useful Improvements in Throat-Plates for Sewing-Machines, of which the following is a specification, reference being had therein to the accompanying drawings.

10 This invention relates to that class of sewing-machines used for different kinds of special work and which require different kinds of needle throat-plates in changing from one kind of work to another; and the invention 15 has for its object to provide the work-support with interchangeable throat-plates of different kinds which will always be conveniently present for use, so that one may be removed from and the other be placed in working position 20 when changing from one kind of work to another.

The particular machine to which the invention is in the present instance applied is a machine for stitching dash-frames for carriages. In doing some parts of the work a flush or level throat-plate is desired; but in stitching the leather or other coverings over the round or half-round iron rods which stiffen the dash-frames a raised throat-plate is 30 required. Two interchangeable throat-plates are preferably hinged or pivoted to the work-support in such locations that either may be turned over into working position when the other has been turned over out of the way, 35 one of said throat-plates being plain or smooth, so as preferably to lie flush or even with the top of the work-support, and the other of said throat-plates having a raised portion in which the needle-hole or throat is 40 formed, and which raised portion will properly support the work around the needle when stitching the covering to the dash-frame rods. The work-support is preferably provided with suitable recesses in which the interchangeable 45 throat-plate not required for use will be housed when removed from its working position.

In the accompanying drawings, Figure 1 is a perspective view showing the upper part of 50 the work-support of a dash-frame sewing-

machine embodying the present invention. Fig. 2 is a sectional view of the invention.

Referring to the drawings, 12 denotes the upper part of the work-support, to which is pivotally attached the plain throat-plate 13 and the special throat-plate 14, having the raised work-sustaining lug or part 15, in which the needle-hole or throat is formed. The work-support is provided with a groove or recess 16, which is of a proper size and depth 55 to receive the body of either throat-plate, so that the upper surface of the body of either plate will be flush, or approximately so, with the top of the work-support when in working position, the lug or part 15 of the special 60 throat-plate 14 projecting above the top of the work-support when the said special throat-plate is in working position, as shown in Fig. 1.

The sloping sides of the work-support are provided with grooves or recesses 17 and 18 65 of proper size to receive, respectively, the throat-plates 13 and 14 when either is not in working position and in which grooves or recesses the said throat-plates will be housed and out of the way when not in use. 70

From the foregoing it will be understood 75 that the invention provides a plurality (two or more) of interchangeable throat-plates movably attached to the work-support of a sewing-machine in such a manner that either 80 of them may be readily adjusted to working position or removed therefrom simply (in the form of the invention herein shown) by turning it over on its hinge or pivot 19. Thus either throat-plate, being movably attached 85 to the work-support, will always be present for use when required, so that it cannot be accidentally misplaced or lost and can be conveniently thrown into or out of working 90 position and when not in use will be entirely 95 out of the way.

The invention is not to be understood as being limited to the special number or forms of interchangeable throat-plates herein shown and described or to any special manner of 95 movably attaching them to or mounting them on the work-support, as many variations may be made in the details of the invention without departing from the spirit thereof.

Having thus described my invention, I 100

claim and desire to secure by Letters Patent—

1. A sewing-machine work-support provided on opposite sides of the working position of the throat-plate with recesses, as 17, 18, combined with a plurality of interchangeable throat-plates of different characters, as 13, 14, said throat-plates being hinged or pivoted at separated points to the said work-support so that either may be brought into working position or may be housed in its receiving-recess in the work-support when another throat-plate is to be placed in working position.

2. A sewing-machine work-support provided on opposite sides of the working position of the throat-plate with recesses, as 17, 18, combined with the interchangeable throat-plates 13 and 14, one of which is plain and the other of which is provided with a raised projection 15, said throat-plates being hinged or pivoted at separated points to the said work-support

so that it may be turned on its hinge or pivot to be brought into working position or to be housed in its recess when not in working position.

3. The combination with a sewing-machine work-support, of two interchangeable throat-plates of different characters separately hinged or pivoted at two different separated points to said work-support and either of which may be turned on its hinge or pivot to be brought into working position, or to be removed therefrom when the other of said throat-plates is to be brought into working position.

In testimony whereof I affix my signature in presence of two witnesses.

JOHN DOUGLAS.
